UNITED STATES PATENT OFFICE.

CHARLES H. COLLINS, OF CINCINNATI, OHIO.

DESIGN FOR A LABEL.

Specification forming part of Design No. 5,497, dated January 30, 1872.

I, CHARLES H. COLLINS, of Cincinnati, Hamilton county, Ohio, have invented a new and useful Design for a Label for Baking-Powder Packages, of which the following is a specification:

The nature of my design is fully represented in the accompanying printed illustration, to which reference is made.

The design consists essentially of a monogram composed of the initials C. H. C., in the represented fanciful form and arrangement, upon a shield or escutcheon, above which are

the words "C. H. Collins' Paragon Baking-Powder."

I claim as my invention—

The design for a baking-powder label, substantially as represented.

In testimony of which invention I hereunto set my hand.

CHARLES H. COLLINS.
